UNITED STATES PATENT OFFICE.

GEORGE WEST PHILLEO, OF LEADVILLE, COLORADO, ASSIGNOR TO AMERICAN SMELTING & REFINING COMPANY, A CORPORATION OF NEW JERSEY.

GREASING DEVICE.

1,317,217.

Specification of Letters Patent. Patented Sept. 30, 1919.

Application filed February 24, 1917. Serial No. 150,747.

To all whom it may concern:

Be it known that I, GEORGE WEST PHILLEO, a citizen of the United States, and resident of Leadville, in the county of Leadville and 5 State of Colorado, have invented certain new and useful Improvements in Greasing Devices, of which the following is a specification.

My invention relates to a lubricating device of general application but particularly 10 designed for use in greasing the track engaging surfaces of traveling members where the track and members are subjected to intense drying conditions such as are formed 15 in a sintering machine.

In sintering machines of Dwight and Lloyd type, it is usual to deposit a charge of the ore to be sintered on an endless chain of traveling pallets, and after igniting the 20 charge to cause the pallets to pass along tracks and over series of wind or vacuum boxes arranged to draw the combustion zone of the ignited ore charge downward through the same. Any grease or other lubricant 25 which may be applied manually to the pallets or tracks quickly dries and much difficulty has been experienced in maintaining the pallets and their engaging portion of the track sufficiently lubricated. Under present 30 methods there is a material waste of the lubricating substance; it collects in spots or runs over the side of the tracks and requires the attention of some one to maintain the parts sufficiently lubricated and otherwise 35 the old methods are expensive and inconvenient.

Accordingly, one of the objects of the invention is to provide a simple form of lubricating device for applying a lubricant automatically to the wearing surface between the 40 tracks and the pallets. Another object is to provide means for supplying the lubricant in economic quantities and distributed in such a manner as to maintain just the necessary lubricated condition to the parts even 45 in the presence of the rapidly evaporating conditions incidental to a heating machine such as the sintering machines.

Another object of the invention is to provide a lubricating device of the plunger feed 50

type which is simple in structure, formed of relatively few parts, which can be readily demounted for re-charging or for repairing and each charging element of which will become inoperative automatically when the 55 lubricant has been discharged therefrom.

Incidental to the desire to provide a simple form of lubricating device which will distribute the lubricant economically, a further object is to provide a construction 60 which can be readily installed upon the sintering machine and which can be actuated from the same mechanism which drives the pallets along the track.

Various other objects and advantages of 65 the invention will be in part obvious from an inspection of the accompanying drawings and in part will be more fully set forth in the following particular description of one form of mechanism embodying my invention, and the invention also consists in certain new and novel features of construction and combination of parts hereinafter 70 set forth and claimed.

In the accompanying drawings: 75
Figure 1 is a view in side elevation showing part of a Dwight and Lloyd sintering machine with a preferred embodiment with my invention installed thereon;

Fig. 2 is a plan view of the device shown 80 in Fig. 1;

Fig. 3 is a view in side elevation of a bank of lubricating grease cups shown in reduced scale in Fig. 1;

Fig. 4 is a view taken on the line 4—4 of 85 Fig. 3;

Fig. 5 is a plan view looking down on the device shown in Fig. 3, and

Fig. 6 is an enlarged view showing the eccentric of Fig. 2. 90

In the drawing there is shown a conventional form of Dwight and Lloyd sintering machine, including a pair of upper tracks or runways 10, for the endless chain of pallets 11 which are caused to move along the tracks 95 and over wind or vacuum box 12 by a suitable driving mechanism 13, all as is usual with devices of this character.

The machine is provided with a lubricating device of the slow feed plunger type ar- 100

ranged to discharge the lubricant through the tracks and into the path of the moving pallets at a plurality of points 14 spaced along the length of the tracks a distance depending, among other considerations, upon the lubricant drying conditions present in the normal actuation of a sintering machine of the class described.

Each of these points 14 is connected by means of a conduit 15 with one of a bank of grease cups in the form of cylinders 16 mounted on the machine in a position convenient for receiving a recharge of lubricant as the cups are exhausted. These cups are shown in a position so as to minimize undue heating thereof by the burning ore, although it is to be understood that if some heavy form of grease is used as a lubricant, it may be desirable to install the grease cups at some warm portion of the machine so as to facilitate an easy flow of the grease to the usual points of application along the length of the tracks. All of these grease cups are similar in construction so that a detailed description of any one cup will be sufficient for any one in the bank. The grease cups illustrated are made from $2\frac{1}{2}$ inch cold drawn tubing opened at opposite ends and threaded internally throughout their length with threads of relatively low pitch. An ejecting plunger 17 preferably a brass plug is threaded to fit in the cylindrical cups and is mounted on a square cold rolled bar constituting a stem 18 which is passed through a squared opening in a bushing 19 rotatably mounted in a guiding sleeve 20 coacting with the bushing to close one end of the cylinder. The opposite end constitutes a wide open inlet for charging the grease cup and is closed by means of a plug 21 demountably threaded into the inlet end. The lubricant receiving end of the conduit 15 is threaded into the side of the cup adjacent the plugged end and is so arranged that the conduit and cup may be separated readily.

The plunger is rotated and thus advanced slowly through the grease cup by means of a pawl and ratchet feed actuated from the driving mechanism 13. This connection includes a ratchet wheel 22 provided with a relatively large number of teeth fixed to the bushing 19. The pawl 23 of the feed is pivoted on a shaft 24 rotatably mounted in a rocker arm 25 mounted for oscillating movement about the axis of rotation of the plunger and its stem. Each of the ratchet wheels are normally held from rotation in the opposite direction by means of retaining pawl 26 such as are usually found in pawl and ratchet feed mechanisms. The rocker arm has an extension 27 provided with a slot 28 extending lengthwise therein and in a line passing through the axis of rotation of the plunger. The several exten-

sions projecting from the grease cups extend from the bank of the cups in the same direction and are each pivotally connected by means of a roller pin 29 projecting through the slot and engaging with lugs 30 projecting from one side of a reciprocating rod 31. The rod 31 is linked to the frame of the machine or to the frame supporting the grease cups and is reciprocated by means of a connecting rod 32 one end of which is pivotally connected with the rod 31 and the opposite end of which is actuated by an eccentric 33, mounted upon the shaft 34 which in turn is actuated through reducing gears 35 from the pallet driving mechanism 13.

The shaft 24 carrying the pawl is provided with a laterally extending lug 36 and the outer end of the stem 18 is provided with a crank arm 37 designed, at the end of the movement of the plunger in the grease cup to swing into engagement with the lug 36 and thus swing the pawl into an inoperative position disengaged from the ratchet wheel. The crank arm 37 is provided with a handle 38 by means of which the plunger may be re-rotated into its initial position to receive a fresh charge of the lubricant.

In operation, and with the grease cups charged with a suitable lubricant, the driving mechanism for the pallets will act through the eccentric to reciprocate the several rocker arms and will act therethrough and through the pawl and ratchet feeds to advance the plungers through the several grease cups with a slow step by step movement thus forcing the lubricant through the conduits to their several points of application along the track of the sintering machine.

Should it be desired to vary the rate of the feed of lubricant, at any point relative to the rate of movement of the traveling pallets the nuts holding the roller pin 29 in position are loosened and the roller pin 29 moved along the slot thus varying the arc of movement and accordingly the number of teeth of the ratchet engaged by the pawl at each actuation of the reciprocating rod.

As any plunger approaches the discharge end of its grease cup, the rotating crank arm 37 is brought into engagement with the lug 36 and acts thereon to rotate the same in a direction to move the pawl into position disconnecting the same from the ratchet wheel and thus intercepting the operation of any exhausted cup forming a part of the lubricating device. When the pawl is in disconnected position the plunger may be returned to its initial position by engaging the handle 38 and re-rotating the plunger into its first position. The plug end may then be opened with a spanner wrench and

5 a new charge of lubricant inserted in the cup after which the closure may be replaced, the pawl may be moved into active engagement with the ratchet and the operation repeated.

10 By means of a device of this character a definite and regulated amount of lubricant may be fed to the pallets as they move along the tracks thus attaining a material saving in the cost of operation over the methods previously used on these sintering machines. The lubricant obviously may be applied at as many points as desired so that a constant supply is insured even under the 15 extreme heat conditions present in these machines. The rate of feed is usually regulated so that just the requisite amount is supplied to afford the necessary lubrication under the variable conditions of service to 20 which such machines are subjected from time to time and individual adjustment of the supply to any one point is provided.

25 The several parts are such as can be made in any machine shop and do not require any special stock or tools for this construction. The conventional form of sintering machine does not have to be modified to permit of the installation of such a lubricating device and the necessary power is conveniently 30 available from the pallet driving mechanism.

35 While I have shown and described, and have pointed out in the annexed claims, certain novel features of my invention, it will be understood that various omissions substitutions and changes in the form and details of the device illustrated and in its operation may be made by those skilled in the art without departing from the spirit of the 40 invention.

Having thus described my invention I claim:

1. In a sintering machine, the combination with a track for supporting the traveling pallets and power mechanism for actuating the pallets, of a lubricating device having a discharge end opening through the pallet engaging surface of the track, said device including a reservoir for the lubricant, a 45 conduit connecting said reservoir with said discharge end and pressure creating mechanisms operatively connected to said power mechanisms to be actuated thereby for feeding the lubricant in a solid stream from the 50 reservoir through said conduit and track.

55 2. In a sintering machine, the combination with a track, a series of pallets mounted to travel on said track, and means for driving said pallets, of a reservoir for a lubricant, and means geared to said pallet driving means for feeding the lubricant slowly from the reservoir to the traveling pallets.

60 3. In a sintering machine, the combination with a track, a series of pallets mounted

65 to travel on said track and means including a reducing gear train for moving the pallets, of means actuated by said pallet-moving-means for feeding a lubricant to the track engaging surface of the pallets, whereby the lubricant will be fed to the track at a 70 rate proportionate to the rate of travel of the pallets on the track.

4. In a sintering machine, the combination with a track, a series of pallets mounted to travel on said track, means positioned at 75 one end of the machine for moving the pallets, of means actuated by said pallet-moving-means for feeding a lubricant to the track engaging surface of the pallets, and means for regulating the rate of lubricant 80 feed per unit of travel of the pallet moving means.

5. In a sintering machine, the combination with a track for supporting pallets and driving mechanism for moving the pallets 85 along the track, of a lubricating device provided with means for feeding a lubricant to the pallets at a plurality of points spaced along the length of the track and means mechanically coupled to and actuated from 90 said pallet moving mechanism for feeding the lubricant.

6. In a sintering machine, the combination with a track for supporting pallets and mechanism for moving the pallets along the 95 track, of a lubricating device driven directly by said mechanism and provided with a plurality of means for feeding a lubricant to the pallets at a plurality of points spaced along the length of the track, said feeding 100 means being operatively independent of each other.

7. A lubricating device including a tubular member for containing the lubricant, a plunger threaded in said member so as to 105 advance the plunger in the member by the rotation of the plunger, a pawl and ratchet feed for rotating the plunger, and means controlled by the position of the plunger in the member acting directly on the pawl to 110 swing the same into an inoperative position relative to the ratchet.

8. A lubricating device, including a tubular member for containing the lubricant, an ejecting plunger mounted for longitudinal 115 movement in said member, means for actuating the plunger, said means including a pawl and ratchet feed, and means movable with the plunger for engaging the pawl to move the same into an inoperative position 120 relative to the ratchet as the plunger approaches the end of its travel in the member.

9. A lubricating device, including a tubular member for containing the lubricant, an ejecting plunger mounted for longitudinal 125 movement in said member, means for actuating the plunger, said means including a pawl and ratchet feed, said feed including a

lug fixed to the pawl to swing the same, means movable with the plunger for engaging the lug to move the pawl into an inoperative position relative to the ratchet as the 5 plunger approaches the end of its travel in the member.

Signed at Vancouver, in the county of

Vancouver and Province of British Columbia, Canada, this twenty-fourth day of January A. D., 1917.

GEORGE WEST PHILLEO.
